COOKING STOVE

Henry R. Johannes, Allentown, Pa., assignor to Caloric Corporation, Topton, Pa., a corporation of Pennsylvania

Filed Apr. 7, 1964, Ser. No. 79,377

Term of patent 14 years

(Cl. D81—4)

Fig. 2.

Fig. 1.

FIG. 1 is a front perspective view of a cooking stove embodying my new design, the opposite side being the same as that shown and the back being plain.

FIG. 2 is a top plan view of the same.

The grid lines, parallel horizontal lines and parallel vertical lines indicate contrast.

The dominant features of my design reside in the portions shown in full lines.

I claim:

The ornamental design for a cooking stove, as shown and described.
